UNITED STATES PATENT OFFICE.

FREDERICK KOHNLE, OF DAYTON, OHIO, ASSIGNOR TO THE MONARCH TAG COMPANY,
OF DAYTON, OHIO, A CORPORATION OF OHIO.

PRICE-TAG.

1,272,057.

Specification of Letters Patent.

Patented July 9, 1918.

Application filed November 12, 1917. Serial No. 201,435.

To all whom it may concern:

Be it known that I, FREDERICK KOHNLE, a citizen of the United States, and residing at Dayton, in the county of Montgomery and State of Ohio, have invented a new and useful Improvement in Price-Tags, of which the following specification is a full disclosure.

The invention relates to a fastening device, particularly as a price tag fastener formed of wire.

An object of the invention is to provide a tag fastener of a wire bent into plural ply and formed to be permanently fastened to the tag with no sharp points or ends exposed or protruding which might injure the material to be tagged or scratch the hands or the surface which may be engaged thereby.

Another object of the invention is to provide a wire staple tag fastener having plural ply prongs, each formed of a portion of wire bent upon itself to form a round pin end and a plural ply yoke or head portion comprising a plural number of members pressed together side by side and engaged with the tag to rigidly anchor the fastener and hold the prongs in an alined position at right angles or perpendicular to the plane of the tag.

Another object of the invention is to provide a wire tag fastener having prongs which penetrate the material to be tagged, adapted to be interlockingly engaged and clenched upon the goods and in which the ends of the wire of the fastener lie on the underside of the tag.

Various other objects, features and advantages of the invention will be more fully set forth in the following specification and description of the drawings, forming a part hereof, and in the drawings like characters of reference denote corresponding parts throughout the several views, of which:

Figure 1 is a plan view of the face side of a pin ticket or price tag containing my improved fastening device.

Fig. 2 is an end edge view of the tag and fastening shown in Fig. 1.

Fig. 3 is an enlarged section taken on line 3—3, Fig. 1.

Fig. 4 is a perspective view of the fastener.

Fig. 5 is a plan view of the tag of the side opposite to that shown in Fig. 1.

Fig. 6 is a view showing a step of inter-

lockingly clenched prongs of the fastener on 55 the reversed side of the ticketed material.

Fig. 7 is a view showing a tag fastened to the goods.

Fig. 8 is a perspective view of a tag and fastener, the fastener being of modified construction of the type shown in the other figures of the drawing.

Referring to the drawings, 1 indicates a cardboard price tag, which at its upper edge contains my improved fastener rigidly 65 clenched to the tag, so that its prongs, which penetrate the material or goods to be ticketed, project perpendicularly to the plane of the tag.

The fastener is made from a single length 70 of wire bent to form a plural ply staple, which is rigidly clenched to the tag to project its prongs in a position upright or perpendicular to the plane of the tag. This is essential, so that the tag can be easily and 75 conveniently fastened to the goods, and also to maintain an alinement between the fastener prongs of a series of tags unitarily combined in a gang strip, possessing the characteristics of the tag strip disclosed in 80 a prior patent issued to me March 2, 1915, numbered 1,130,614, adaptable for use in price marking and tag applying machines.

The process of forming a single length of wire into a fastener, securing and clenching 85 it to the tag, possesses developments herein regarded as distinct and separate from the finished product as an article of commerce. Therefore, the description will be confined to the product and its method of application to the goods to be tagged. The fastener when bent to form and clenched to the tag represents a staple, having a plural ply yoke portion 2, preferably comprising three parallel strands pressed together and extending 95 crosswise of the tag marginally at the upper edge of the tag. From the yoke portion 2 the strands pass through the tag to the opposite face of the tag, are then bent to provide portions extending inward for a 100 predetermined length parallel with and from each end of the yoke 2 upon the rear face of the tag to form U-bends 3, which together with the yoke provides a fastener head. The wire ends 4, 4, respectively come opposite 105 each other as strands of the U-bends, with the edge on the rear face side of the tag presenting a smooth front tag face devoid

of any points or sharp portions to scratch or prick the hands or goods. From the fastener head the strands at points 6, 6', are bent at right angles from the hook or U-bends to form a pair of prongs or shank members of double ply, pressed together at the portions 8, 8, to form rounded ends for penetrating the goods by separating the threads or fibers without injuring the threads or fibers.

In the modified form of fastener, shown in Fig. 8, the prongs or shanks are of double ply, the strands or members pressed together throughout their length, which penetrate the goods and are clenched in a manner similar to the now prevailing practice of fastening the commercial or common single strand staple.

As shown in the other figures of the drawings, each prong is formed with a straight strand or part 7 and a crooked strand or part 7', separated from its companion part 7, providing an opening to insert the other or second prong of the staple therethrough for interlocking the prongs in fastening the tag to the goods. This provides a permanent fastening and one in which the tag cannot be pulled from the goods in handling.

Figs. 6 and 7 illustrate steps in the method of interlocking and clenching the prongs. After the prongs have been pressed through the goods, one prong is bent toward the other or second prong, looped or engaged about said second prong and then clenched or bent down upon the rear side of the goods tagged, after which the second prong is bent and clenched in the same direction as the first, interlocking and clenching the prongs upon the material, avoiding sharp points or edges. The prongs may be simultaneously clenched after one has been inserted over the other. The head of the fastener being of a plural ply, with the strands pressed together, side by side, provides an increased bearing engagement with the opposite faces of the tag for rigidly anchoring the head to the tag to hold the prong aloft or in a perpendicular plane to the plane of the tag.

The fastener, with all of its parts formed of a plural ply, permits in its manufacture the use of a smaller gage wire than heretofore used in the making of the present commercial staple or wire fasteners, having increased stability in addition to its other advantages.

The fastener, as above described in detail, may be defined as composed of a single length of wire bent to form to comprise a plural ply head, having crimped opposite ends and a pair of plural ply prongs diverting from the ends at right angles to the head.

The penetrating and attaching members as a pair of parallel pins, each constituting a doubled piece of wire presenting a

smooth rounded penetrating point and spread apart shank strands for looping one pin to the other, necessarily need not be made from a single piece of wire and within the aspect of this invention may represent 70 separate pin members independently secured to the tag to project from one side and relatively arranged so that one may be engaged through the other to interlock with each other when crimped through and upon the 75 goods to be ticketed.

Having described my invention I claim:

1. A tag fastener composed of a single length of wire bent into plural ply and formed to comprise a yoke head portion having crimped ends, adapted to engage through a tag and be clenched upon opposite side of the tag, and a pair of prongs diverting from the crimped ends of the head in a direction perpendicular to the plane of the 85 head, each prong having a rounded pin end.

2. A tag fastener composed of a single length of wire bent into plural ply and formed to comprise a yoke head portion crimped at each end to provide hooks arranged to engage through and upon the opposite face of a tag, the ends of the wire respectively forming a ply of the hooks and engaging the rear side of the tag, and a pair of prongs diverting from the ends of the 95 hooks at right angles to the plane of the head having rounded pin ends.

3. A tag fastener comprising a length of wire with a pair of pin portions each with a rounded end, adapted to be inserted in the 100 material to be tagged, and an integral plural ply yoke portion of hook formation at each end, the hooks including the free ends of the wire, and said free ends of the wire arranged to engage with the rear side of the 105 tag.

4. A tag fastener comprising a piece of wire bent to form a pair of double ply pin portions, each composed of two members having a rounded joining end, and a plural 110 ply head portion integrally connecting said pin portions, said two members of each pin portion separated from each other between the said rounded end and head to provide an opening for interlockingly engaging one 115 pin portion with the other.

5. A tag fastener comprising a piece of wire bent upon itself into plural ply and bent to form a head portion and pair of prongs, each prong composed of a portion 120 of the wire bent upon itself to compose two members and a rounded prong end, and the members separated from each other intermediate the rounded joining end and head, adapting the prongs to be interlockingly 125 engaged one with the other and clenched upon the material to be tagged.

6. A pin ticket comprising a card and a penetrating and attaching member constituting a single piece of wire bent upon itself 130

to present a pair of double ply penetrating pins with smooth rounded points, and a plural ply head connecting the pins consisting of a straight intermediate portion 5 and crimped bends at the opposite ends of the straight portion, each crimp bend engaging through the card and clenched upon the opposite sides thereof.

7. A pin ticket comprising a card and 10 penetrating and attaching member constituted of a single piece of wire passed through and clamped by bends therein to the card, and presenting a pair of pins projecting from one side of the card, the wire 15 in the pin portions being continuous and doubled to present smooth rounded penetrating points, and spread apart shank strands for looping one pin through the other.

8. A pin ticket comprising a card and 20 penetrating and attaching members comprising a pair of pins fixed to and projecting from one side of the card and parallel to

each other, each pin constituting a doubled piece of wire to present a smooth, rounded, penetrating point and spread apart shank 25 strands for looping one pin through the other.

9. A pin ticket comprising a card and penetrating and attaching members, said members comprising a pair of pins fixed to 30 and projecting from one side of the card and disposed to be interlooped one with another, each pin constituting a doubled piece of wire to present a smooth, rounded penetrating point and one thereof having its 35 shank strands spread apart for engaging the other therethrough.

In witness whereof, I hereunto subscribe my name, as attested by the two subscribing witnesses.

FREDERICK KOHNLE.
